UNITED STATES PATENT OFFICE.

GERALD G. GREULICH, OF CLEVELAND, OHIO.

FLOOR TILE AND FLOOR CONSTRUCTION.

Application filed July 5, 1921. Serial No. 482,524.

To all whom it may concern:

Be it known that I, GERALD G. GREULICH, a citizen of the United States, residing at Cleveland, in the county of Cuyahoga and State of Ohio, have invented a certain new and useful Improvement in Floor Tiles and Floor Constructions, of which the following is a full, clear, and exact description, reference being had to the accompanying drawings.

This invention relates to floor tiles and to floor constructions embodying such tiles. More particularly, my invention is concerned with the provision of tile and concrete floors, wherein concrete joists are supported in parallel rows and are bridged by hollow tile.

One of the methods heretofore employed for constructing floors is to pour concrete joists, substantially rectangular in cross section, in built-up forms which are removed and discarded after the concrete has set. Usually these joists are arranged in equally spaced, parallel rows, and are bridged by sections of tile which are considerably less in thickness than the depth of the joists. In constructing a floor according to this method, I have found that considerable time is required in placing and removing the forms; that a needless amount of concrete is employed by constructing rectangular joists, and that frequently a soffit piece must be secured between the joists after the forms are removed. Furthermore, I have found that in a construction of this character, it is difficult to accurately position the reinforcing steel within the joists, and accordingly the joists are liable to be materially weakened.

One of the objects of my invention therefore, is the provision of a floor having joists which are supported in parallel rows, and which are arranged to be bridged by tile which interlock with the concrete in each row. In this connection, the tiles to be used extend the entire depth of the joist and themselves provide a form into which the concrete may be poured, thereby eliminating the necessity for temporary forms.

Another object is the provision of a form of joist which effects quite a material saving in concrete, and at the same time possesses sufficient strength to carry the floor load. In this connection the cross-section shape of the joist is adapted to facilitate the positioning of the steel reinforcement so

that the concrete while being poured will not move the lower steel rods and thereby cause them to be so positioned that they are uncovered when the concrete dries.

Still another object is the provision of a tile, which may be formed on customary tile forming machinery, and which may be provided with suitable bracing members for transmitting the load stresses directly to the joists, without requiring the center lines of the joists to be positioned closer together than is employed with present forms of construction.

In carrying out my invention, I employ rows of tile, each tile being approximately the depth of the joist to be employed, and I position the tile in parallel rows equally spaced, and such distance apart that the space between them is of the proper size for a concrete joist to be poured therein. Extending across the space between adjacent rows of tile, and in a plane with the bottom thereof, I prefer to provide soffit pieces which automatically space the adjacent tile, and form a bottom for receiving the concrete, and at the same time provide a surface which is readily adapted to receive plaster on the exposed side thereof.

In placing the tile, the only form work required comprises a horizontal table which may be rough planking supported by the floor beneath. After the tiles are arranged in parallel rows and the soffit pieces positioned between the rows, the steel reinforcement is placed in the usual manner and the concrete poured. The tile itself constitutes the form, and at the same time provides a strong surface on which the men may work during the pouring operation.

The means for accomplishing the above objects will be more fully set forth in the following description, which relates to the drawing, and the essential characteristics of my invention which include the method, the floor, and the tile will be set forth in the claims.

In the drawings, Fig. 1 is a plan of a floor constructed in accordance with my invention; Fig. 2 is a cross section through one of the joists, showing in detail the interlocking features between the concrete and tile; Fig. 3 is a perspective view showing a form of tile employed; and Fig. 4 is an enlarged section through one of the joists.

My invention contemplates, in general,

the provision of a floor which as above stated embodies parallel rows of equally spaced concrete joists with tile positioned between the joists and interlocked with the 5 sides thereof. In Fig. 2, I have shown the joists 10 as extending from the floor surface, on one side, approximately to the ceiling surface, on the other side, and as being provided with the customary reinforcement 13 10 near the top and bottom surfaces thereof.

In Figs. 2 and 4 it will be noted that each joist is wider at the top and bottom, than it is in the middle, and that the tile positioned on each side thereof, is interlocked 15 not only by the serrations in the face of the tile, but also by the peculiar shape of the vertical faces which are adjacent the joist. In Fig. 4 particularly, it is to be noted that shoulders 14 are provided adjacent 20 the bottom of the joist, and that the vertical face 15 of the tile is positioned directly above the shoulders. Near the upper part of the joist I provide shoulders 16 which are flared outwardly with a gradual 25 curve corresponding with the shape of that portion of the tile adjacent the top corners thereof.

In constructing a joist according to the plan mentioned, there is quite a material 30 saving of concrete, because of the fact that the middle portion of the joist is materially reduced in width. A joist having a form of this character possesses sufficient strength 35 to withstand any shearing stresses incident to floor loads between the supporting girders, and at the same time provides sufficient concrete, to withstand the bending moments, the top flange taking care of the compressive stresses resulting from positive 40 moment at centers of spans and the bottom flange taking care of compression stresses resulting from negative moment at points of support.

Positioned between adjacent joists I provide 45 rows of tile indicated generally at 20. Each tile is shown as comprising a hollow member, open at both ends, and as having a top face 21 a bottom face 22, and side walls composed of intermediate vertical portions 15, upper inclined portions 17 and rounded shoulders 18, and lower inclined portions 19 and nearly vertical but slightly 50 inwardly inclined portions 29. There are also internal webs 25.

As shown in Fig. 1, the tiles are positioned 55 end to end, intermediate the joists, and in the manner now employed for laying tile for similar floor construction. Each tile is shown as extending from the top to 60 the bottom of the joist, and as being maintained in spaced relation to each other, prior to the pouring of the concrete, by the soffit pieces 12.

Since the load stresses on a beam supported 65 at both ends vary uniformly with

the distances from the point of support, I have provided inclined bracing members 25, which extend from the top to the bottom of the tile and throughout the entire length thereof. In Figs. 2 and 3 it is to be noted 70 that the points of engagement between the inclined members and the top surface of the tile, as at 26, are approximately equally spaced, with relation to the top shoulders 18, and with relation to each other. At the 75 bottom, however, the inclined members do not extend to the corners of the tile, but are each spaced inwardly therefrom, as at 28, whereby sufficient space may be provided 80 between the wall 15 and the inclined members for the insertion of pipes, conduit, and similar material.

The soffit pieces 12 are preferably the same length as the tile, and as shown in Fig. 4, are serrated, as at 30, 31, along the top and bottom surfaces thereof. The serrations are made in accordance with the usual dovetail joint construction to enable the concrete to be embedded in the top surface thereof, for retaining the soffit pieces 90 in position. In laying the tile it is comparatively an easy matter to place the soffit pieces upon the planking and thereby to facilitate the spacing of the tile.

In constructing a floor according to my 95 invention, it is only necessary to erect a temporary platform having a horizontal table, which is positioned in a plane corresponding to the ceiling of the room directly beneath the room in which the floor is to be laid. Sections of tiles 20 are then laid end to end, in parallel rows, upon the platform and are maintained in such spaced relation by soffit pieces 12, which are laid on the platform and between adjacent rows of tile. The reinforcement 13 is then suspended between the tile and concrete poured 100 around such reinforcement. In pouring the concrete it is to be noted, that the lower corners on the vertical faces 15 prevent the reinforcement from moving laterally with 105 relation to the joists.

From the foregoing description, it will 110 be seen that I have provided a floor which effects a material saving in concrete, and thereby materially lessens the dead weight per square foot of floor area and consequently decreases the amount of steel work required for building; that I have provided a floor, wherein the tile employed constitutes the 115 form work for receiving the concrete, and wherein the erection costs are considerably reduced. Furthermore, it will be seen that I have provided a tile which is so constructed, that it is light yet strong enough 120 to provide a floor to work on, until the final fill and finish are applied. In this connection the tile is well adapted for cutting various sizes of holes, through which 125 suitable conduit may extend without effect. 130

ing the load carrying strength of the floor.

Having thus described my invention, I claim:

1. A one-piece building tile comprising parallel top and bottom faces, the top face being narrower than the bottom face, and connecting faces each having the mid-portion thereof in a plane at right angles to the top and bottom, the mid-portion of each connecting face being joined to the top face by an oblique surface, and to the bottom face by surfaces lying in intersecting planes, one of said planes being parallel to the plane of the mid-portion, and the other of said planes lying approximately at right angles to the plane of the oblique surface.
2. A one-piece building tile having the ends thereof open and having parallel top and bottom surfaces with sides extending therebetween, the top and bottom surfaces terminating short of the extreme width, whereby the central portion overhangs the bottom, said central portion lying in a plane at right angles to the top surface, and an oblique surface joining the top and central portions.
3. A one-piece building tile comprising parallel top and bottom faces and parallel end faces, the end faces terminating short

of the top and bottom faces and having oblique surfaces diverging from the end faces and extending toward the top and bottom faces respectively, said oblique surfaces lying in planes approximately at right angles to each other, the lower oblique surface terminating short of the bottom face and the upper oblique surface merging with the top face.

4. A one-piece building tile having parallel top and bottom surfaces and having sides comprising two approximately parallel portions one overhanging the other and connected thereto by an oblique surface, both of said parallel portions lying in planes substantially at right angles to the top and beyond the side edges thereof.

5. A one-piece building tile having parallel top and bottom surfaces and having sides each comprising at least two approximately parallel portions, one of which overhangs the bottom of the tile and lies in a plane at right angles to the top and bottom surfaces, the other of which extends inwardly from the bottom of the tile, and an oblique surface extending between said parallel side portions.

In testimony whereof, I hereunto affix my signature.

GERALD G. GREULICH.
